UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,755, dated February 7, 1882.

Application filed January 12, 1882. Term of patent $2\frac{1}{2}$ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of the light center 10 A, showing the straight sides and bounded elsewhere by foliage and flowers, the light center B, having one of its sides notched and partly covered with floral and foliage ornamentation, and the elongated rectangular figure C.

I claim—

The design for a carpet, substantially as shown and described.

In testimony whereof I have signed my name to this specification, in the presence of two subscribing witnesses, this 10th day of January, 15 A. D. 1882.

THOMAS J. STEARNS.
